HEATER OF FLUIDS

Marion W. Barnes, Chicago, Ill., assignor to Universal Oil Products Company, Chicago, Ill., a corporation of Delaware

Application January 26, 1942, Serial No. 428,240

4 Claims. (Cl. 122—356)

The invention relates to an improved form of heater for fluids which is particularly advantageous as applied to heating hydrocarbons to the high temperatures required for their thermal or catalytic conversion. The features of the invention will also be found useful in numerous other applications wherein it is desired to heat one or more streams of fluid with relatively high rates of heat input.

The heater herein provided is of the general type employing a plurality of separately fired cells with tubular fluid conduits disposed adjacent an unfired refractory wall in each cell to receive direct radiant heat on one side from flames and hot combustion gases passing through the cell and from the fired wall of the cell over which said flames and hot combustion gases are passed and to receive reflected radiant heat on the opposite side from the adjacent unfired refractory wall.

The features and advantages of the invention will be apparent to those familiar with the art from an inspection of the accompanying diagrammatic drawing and the following description thereof.

The drawing represents a cross-sectional elevation of one specific form of the heater provided by the invention.

Referring to the drawing, the form of heater here illustrated comprises substantially vertical refractory side walls 1 and 2, sloping refractory walls 3 and 4 extending upwardly and inwardly from walls 1 and 2 to other vertical refractory walls 5 and 6, a floor 7 and end walls, not shown.

Interior refractory walls 8 and 9, spaced from each other and from the side walls 1 and 2, are provided within the heater and extend from the floor to a level adjacent the upper extremity of walls 5 and 6.

Another refractory interior wall 31 is provided substantially midway between walls 8 and 9 and extends from the floor, preferably to a level well above the upper extremity of walls 8 and 9.

The space within the heater between walls 1 and 8 comprises a combustion and radiant heating zone or fired cell 10. A similar separately fired combustion and radiant heating zone or cell 11 is disposed between walls 2 and 9.

Another separately fired combustion and radiant heating zone or cell 12 is disposed between walls 8 and 31 and similar separately fired combustion and radiant heating zone or cell 13 is disposed between walls 9 and 31.

A bank 14, comprising in the case illustrated two vertical rows of horizontally disposed tubular

fluid conduits 15 is located within cell 10 adjacent the interior surface of wall 1. A similar bank 16 comprising two rows of horizontally disposed tubes 17, is located in cell 11 adjacent the inner surface of wall 2. Another bank 18, comprising in the case illustrated a single substantially vertical row of horizontally disposed tubes 19, is located within cell 12 adjacent wall 8 and a similar bank 20 of tubular fluid conduits 21 is disposed in cell 13 adjacent wall 9. Another bank 22, comprising in this instance two substantially parallel rows of horizontally disposed tubes 23 is located adjacent and substantially parallel to the sloping wall 3. A similar bank 24, comprising two rows of horizontally disposed tubes 25, is located adjacent and substantially parallel to the sloping wall 4. Another tube bank 26, comprising a plurality of superimposed horizontal rows of horizontally disposed tubes 27, is located in the fluid heating zone 28 defined between walls 5 and 6.

The entire furnace structure is mounted upon a suitable foundation which, in this instance, comprises a vertical wall 32 disposed beneath each of the walls 1, 2, 8, 9 and 31, a floor 33 disposed beneath and spaced from the refractory floor 7 and suitable footings, not illustrated. Burner compartments 36, 37, 38 and 39, individual to the respective combustion and heating zones 10, 11, 12 and 13 are provided between floors 7 and 33 and between the walls 32. Openings 45 and 50 are provided in each of the outer foundation walls 32 beneath walls 1 and 2 and an opening 51 is provided through each of the foundation walls 32 beneath walls 8 and 9.

A partition 35 separates the space between the foundation walls 32 beneath walls 1 and 8 and between floors 7 and 33 into an upper compartment which comprises the burner compartment 36 and a lower compartment which communicates with burner compartment 38. Another partition 36, disposed between the foundation walls 32 which lie beneath walls 2 and 9, separates the space beneath cell 11 and between floors 7 and 33 into an upper compartment which comprises the burner compartment 37 and a lower compartment which communicates with burner compartment 39.

A horizontal row of burners, one of which is indicated at 40, is provided within burner compartment 36 and these burners communicate with combustion and heating zone 10 through firing ports 41 provided in floor 7 adjacent the lower end of wall 8. Fuel is supplied to each of the burners 40 through a line 42 and control valve 43 and air is admitted in regulated amounts to

burner compartment 36 through opening 45 by adjustment of a suitable damper 44 provided at the mouth of the opening. The air thus admitted to compartment 36 passes through burners 40 to mix with the fuel and form a combustible mixture which is projected into and burned adjacent the surface of wall 8 within zone 10. The flames and hot combustion gases issuing from burners 40 and burner ports 41 are directed upwardly at an angle against and over the surface of wall 8, heating the latter to a highly radiant condition and direct radiant heat is transmitted from wall 8 and from the flames and hot combustion gases passing thereover to one side of each of the tubes of bank 14. Reflected radiant heat is transmitted from wall 1 to the opposite side of these tubes.

A firing arrangement similar to that above described, with the elements thereof designated in the drawing by the same reference numerals 40 to 45 inclusive, is provided in burner compartment 37 for cell 11, which is fired independently of cell 10 and wherein direct radiant heat is transmitted from the hot refractory surface of wall 9 within this zone and from the flames and hot combustion gases passing wall 9 to one side of each of these tubes of bank 16. The opposite side of these tubes is heated by reflected radiation from wall 2.

Another horizontal row of burners, one of which is indicated at 46, is provided in burner compartment 38 for directing flames and hot combustion gases upwardly into zone 12 through firing ports 52 provided in floor 7 adjacent the base of wall 31 and between walls 8 and 31. Fuel is supplied to each of the burners 46 through a line 47, controlled by valve 48, and air for combustion of the fuel is admitted in regulated amounts to burner compartment 38 through the openings 50 and 51 and the space beneath partition 35. The air thus admitted to compartment 38 passes through burner 46 to mix therein with the fuel and form a combustible mixture containing any desired amount of excess air.

The flames and hot combustion gases projected upwardly through zone 12 from burners 46 and burner ports 52 are directed at an angle against and over the surface of that side of wall 31 facing tube bank 18, heating this surface to a highly radiant condition. Direct radiant heat is thus transmitted from wall 31 and from the flames and hot combustion gases passing thereover to one side of each of the tubes of bank 18 and reflected radiant heat is transmitted from wall 8 to the opposite side of these tubes.

A firing arrangement similar to that for cell 12 and designated in the drawing by the same reference numerals 46 to 52 inclusive is provided in burner compartment 39 for cell 13. Cell 13 is thus independently fired and radiant heat is transmitted from that surface of wall 31 facing tube bank 20 and from the flames and hot combustion gases passing over this surface directly to one side of each of the tubes of bank 20. The opposite side of these tubes is heated by reflected radiation from wall 9.

Combustion gases from cells 10 and 12 pass upwardly through the space between sloping wall 3 and the central wall 31 and supply heat by radiation and convection to the tubes of bank 22. Similarly, combustion gases from cells 11 and 13 pass upwardly through the space between sloping wall 4 and the central wall 31 and supply heat by both radiation and convection to the tubes of bank 24. By virtue of the exten-

sion of wall 31 well into the space between the sloping walls 3 and 4, the highly heated opposite surfaces of wall 4, adjacent its upper extremity, transmit direct radiant heat to the tubes of banks 5 22 and 24. Also, by virtue of this extended wall 31 and the restricted cross-sectional area of the combustion gas passageway between its upper extremity and walls 3 and 4, that portion of tube banks 22 and 24 most remote from the source of the flames and hot combustion gases (i. e., the upper portions of the tube banks) are washed by combustion gas streams of higher velocity than the streams of combustion gases emerging from the separately fired cells, thereby increasing the component of convective heat transmitted to the upper portion of tube banks 22 and 24 to assist in compensating for the decreased radiant heat component in the upper portion of these banks.

20 The total combustion gases from zones 10, 11, 12 and 13, after supplying heat to the tubes of banks 22 and 24, pass upwardly through fluid heating zone 28 in intimate contact with the tubes of bank 26 and supply a considerable portion 25 of their residual heat thereto. The combustion gases are thence directed through flue 29 to stack 30.

By independently firing each of the zones 10, 30 11, 12 and 13, entirely independent control is exerted over the heating conditions obtained in each of these zones, and by virtue of the upwardly extended central wall 31, independent control is exerted over the heating conditions prevailing about bank 22 as compared with those 35 prevailing about bank 24. Relatively high rates of heat transmission to the fluid flowing through the tubes is obtainable in each of these zones and an unusually high degree of flexibility with respect to control over the heating conditions in the several zones is provided in this heater. By 40 selection of suitable specific paths of flow for the stream or streams of fluid undergoing heating through the various tube banks and a suitable sequential or parallel arrangement of the tube banks in this flow, a wide variety of heating curves is obtainable for the fluid undergoing treatment and the type of heat treatment desired may be selected to suit requirements. When desired, it is also easy to obtain either a different 45 type of heat treatment or substantially the same heat treatment for two or more separate streams of fluid with the heater herein provided.

The invention is not limited to any specific path of flow for the fluid passing through the 50 various tube banks nor to any specific sequence of flow through the several banks. Ordinarily, adjacent tubes in each bank will be connected in series at their ends by suitable return bends or headers, not illustrated, but it is also within the scope of the invention to provide for the parallel 55 flow of separate streams of the same or different fluid through two or more of the tube banks and, when desired, all or various groups of tubes in each or any bank may be connected for the parallel 60 flow of separate streams of fluid therethrough.

It is also within the scope of the invention to dispose the individual tubes in any or all of the various banks adjacent the side and interior walls of the heater in a vertical rather than a horizontal position and the tubes in either or both of the banks adjacent the sloping walls may extend lengthwise from adjacent the top to adjacent the bottom of the sloping wall rather than from end to end thereof.

The invention also specifically contemplates the substitution of a single row of tubes for the two row arrangement adjacent any or all of the walls 1, 2, and 4 and, when desired, a two row arrangement similar to that shown adjacent walls 1 and 2 may be substituted in either or both of the banks 18 and 20 for the single row arrangement illustrated.

Although the specific form of heater illustrated in the drawing is up-fired with a general upward flow of combustion gases throughout the heater, it is entirely within the scope of the invention to invert the furnace structure and fire in a downward direction with a general downward flow of combustion gases through the heater.

As previously mentioned, a wide variety of advantageous flow arrangements is possible in the improved form of heater herein provided and may be selected within the skill of one familiar with the art and correlate with the firing conditions employed in the independently fired combustion and heating zones to suit requirements.

I claim as my invention:

1. A heater for fluids comprising, in combination, substantially vertical refractory side walls, a substantially vertical refractory interior wall spaced substantially midway between said side walls, another substantially vertical refractory interior wall spaced from and disposed between each of said side walls and the first named interior wall, said wall arrangement providing a combustion and radiant heating zone between each adjacent pair of said walls, a substantially vertical bank of tubular fluid conduits disposed in each of said zones adjacent the surface of one of said refractory walls thereof, and means for independently firing each of said zones comprising burners disposed adjacent one end of that refractory wall thereof opposite said tube bank disposed therein, for projecting flames and hot combustion gases into said zone and over the surface of said opposite wall in a substantially vertical direction, a combustion gas discharge passageway and inclined refractory walls extending therefrom to said side walls, and heating tubes adjacent said inclined walls, the first-mentioned interior wall extending beyond the extremities of the other interior walls into the space between said inclined walls and being fired on its opposite sides whereby to transmit radiant heat directly to the tubes adjacent the inclined walls.

2. A heater for fluids comprising, in combination, substantially vertical refractory side walls, a substantially vertical refractory interior wall spaced substantially midway between said side walls, another substantially vertical refractory interior wall spaced from and disposed between each of said side walls and the first named interior wall, said wall arrangement providing a combustion and radiant heating zone between each adjacent pair of said walls, a substantially vertical bank of tubular fluid conduits disposed in each of said zones adjacent the surface of one of said refractory walls thereof, and means for independently firing each of said zones comprising burners disposed adjacent one end of that refractory wall thereof opposite said tube bank disposed therein, for projecting flames and hot combustion gases into said zone and over the surface of said opposite wall in a substantially vertical direction, each of the tubular elements of said banks being exposed on one side to direct radiation from the flames and hot combustion gases passing through the zone in which it is disposed and

from the surface of said opposite wall, a combustion gas discharge passageway and inclined refractory walls extending therefrom to said side walls, and heating tubes adjacent said inclined walls, the first-mentioned interior wall extending beyond the extremities of the other interior walls into the space between said inclined walls and being fired on its opposite sides whereby to transmit radiant heat directly to the tubes adjacent the inclined walls.

3. A heater for fluids comprising, in combination, substantially vertical refractory side and end walls, an odd number of substantially vertical refractory interior walls spaced from each other and from said side walls and disposed in substantially parallel relation to provide therebetween an even number of separate combustion and radiant heating zones, a substantially vertical bank of tubular fluid conduits disposed in each of the zones adjacent the surface of one of said refractory walls thereof, refractory sloping walls extending inwardly from said side walls to other vertical refractory walls, a fluid heating zone disposed between the last named vertical walls and in communication through the space between said sloping walls with each of said combustion and radiant heating zones, a bank of tubular fluid conduits disposed adjacent and substantially parallel to each of said sloping walls, a bank of tubular fluid conduits in said fluid heating zone, means for independently firing each of said separate combustion and heating zones comprising burners disposed adjacent one end of that refractory wall of each opposite the tube bank disposed therein, for projecting flames and hot combustion gases over the surface of said wall in a substantially vertical direction, one of said interior walls being disposed substantially midway between the first named side walls, being thus fired on opposite sides and extending vertically beyond the other interior walls into the space between said sloping walls, whereby radiant heat is transmitted therefrom to said tube banks adjacent the sloping walls, means for directing combustion gases from each of said separate combustion and heating zones through the space between said sloping walls in radiant heat transmitting relation to the tube banks adjacent the latter, and means for directing combustion gases from the space between said sloping walls through the fluid heating zone in direct contact with the tubular elements of said bank disposed therein.

4. A heater for fluids comprising, in combination, substantially vertical refractory side and end walls, a substantially vertical refractory interior wall disposed substantially midway between said side walls, another substantially vertical refractory interior wall disposed between the first named interior wall and each of the side walls, a combustion and radiant heating zone disposed between each adjacent pair of said refractory side and interior walls, sloping refractory walls extending inwardly and upwardly from the upper extremity of said side walls to other substantially vertical side walls, a fluid heating zone disposed between the last named side walls, a bank of tubular fluid conduits in said fluid heating zone, a bank of tubular fluid conduits disposed adjacent and parallel to each of said sloping walls, a substantially vertical bank of tubular fluid conduits disposed in each of said combustion and radiant heating zones adjacent the surface of one of said refractory walls thereof, means for independently firing each of said combustion and radiant heating zones comprising burners disposed adjacent

the base of that refractory wall of each opposite the tube bank disposed therein, for directing flames and hot combustion gases upwardly over the surface of said wall in direct radiant heat transmitting relation to the tubes of said bank, means for directing combustion gases from said combustion and radiant heating zones through the space between said sloping walls to supply heat by radiation and convection to the tube banks adjacent the latter, and means for direct-

ing combustion gases from the space between said sloping walls through said fluid heating zone in direct contact with the tubular elements of said bank disposed therein, the first mentioned interior wall extending above the upper extremity of the other interior walls into the space between said sloping walls and being fired on its opposite sides whereby to transmit radiant heat directly to the tube banks adjacent the sloping walls.
